UNITED STATES PATENT OFFICE.

FRED E. KUNKEL, OF WASHINGTON, DISTRICT OF COLUMBIA.

GUIDE BAR FOR GUIDE CARDS.

Application filed November 24, 1919. Serial No. 340,319.

To all whom it may concern:

Be it known that I, FRED E. KUNKEL, a citizen of the United States, and resident of Washington, in the District of Columbia, 5 have invented certain new and useful Improvements in Guide Bars for Guide Cards, of which the following is a specification.

In the sorting of cards, sheets of paper, letters, or other flat records, it is customary 10 to use a plurality of partitions successively labelled and arranged in a receptacle such as a sorting tray or filing drawer. The partitions should be sufficiently spaced, one from another, to provide room for the cards or 15 other papers or material to be filed.

Where these partitions, or guide cards as they may be termed, are labelled, the different subdivisions into which they divide the tray vary in size according to relative 20 values placed upon various letters of the alphabet, or a series of numbers, and other divisions used in filing. For instance, if the subdivision is alphabetical, it will be found when the sorting operation is completed, that 25 certain alphabetical subdivisions contain more of the sorted articles than do others. It is, therefore, a requisite that provision be made in spacing the partitions to take into account the varying amounts of room 30 necessary in each subdivision.

As the sorting of such flat articles is an operation, the success of which depends to a large extent upon speed and facility of operation, it is essential that means be provided to hold the partitions in an upright position with the intervening spaces readily available for the reception of articles to be filed. In the same manner it is necessary that the partitions be held in a definite and 35 upright position, slanting backwards, in order that the eye of the operator may select the desired partition swiftly and without effort, dropping his papers or other articles to be filed behind the guide card or partition 40 without having to finger or touch said guide card or partition.

My invention consists in one or more bars which are placed within the sorting tray and parallel to its sides. This bar serves 50 the purpose of holding the partitions substantially vertical and slanting backwards at a predetermined distance from each other, according to a relative table of values which may be compiled for the purpose.

Other objects of my invention will be evi-

dent from the following description and drawings, in which:

Figure 1 is a perspective view of a sorting tray provided with guide bars;

Figure 2 is a fragmental plan view of one of the guide bars;

Figure 3 is an elevation of the same; and Figure 4 is an end view.

The sorting tray or filing drawer, 7, is open at the top and is of sufficient size to accommodate a set of partitions or guide cards, 8. The partitions or guide cards have upwardly extending tabs 9 upon which designations may be marked. In some cases the tabs may be marked with the letters of the alphabet or combinations thereof. In other cases a system of numerical or other designations may be used.

Extending from front to rear of the top of the tray, and parallel to the inner side walls thereof are opposite and complementary guide bars, 10.

These bars may be adjusted by a removable clamp preferably in filing drawers or trays of steel or other composition.

The sides of each guide bar which faces inward of the tray carry a plurality of slots, 13. These slots incline slightly to the rear as will be evident in Figure 3 for a purpose to be hereinafter described and heretofore mentioned.

The positions of the successive slots will be determined by the number of partitions or cards used and the relative number of articles to be filed in each subdivision. The ratio of space between each pair of adjacent slots will be determined by the considerations of the individual cases, and the demands of the articles to be filed. This is predetermined by compiling a table of values for each alphabetical or numerical letter or figure, or other requirements.

The partitions or guide cards, 8, will be inserted in correspondingly marked slots of the two bars and will rest upon the bottom of the tray or file drawer.

Another pair of bars similarly slotted may rest in corresponding positions on the bottom of the tray to hold the bottoms of the guide cards in place. The slight inclination of the slots to the rear will serve to hold the guide cards slightly out of vertical, rendering their inspection easy and the filing of the articles rapid.

Guide bars are moved into position one

at a time and partitions or guide cards inserted in slots, after which one of the guide bars is securely fastened to the sorting tray or filing drawer by means of adjustable and 5 movable clamps. The remaining guide bar is then moved into position, guide cards adjusted to correspond, and the bar securely fastened to the sorting tray or filing drawer in the manner described.

10 The bars, 10, constructed as above described but of indeterminate length are held in position on the upper edge of the sorting tray or filing drawer, 14, by use of the collar 15. This collar 15 conforms to the 15 shape of the bar which slides in the aperture 16 of the said collar and fits frictionally therein. On the opposite sides of the collar are the depending strips 17 and 18. These strips form a saddle and hold the collar, 15, in adjusted position on the edge of the sorting tray.

It will be evident that the bars, 10, may slide in the collars 15, and will thus rest

above the tray in the desired position for holding the guide cards and supporting the 25 articles as they are filed.

It is to be understood that other modifications may be utilized by one skilled in the art and my invention includes all variations within the scope of the appended claims.

30 What I claim is:

1. In combination with a filing tray, a spacing bar for guide cards, means to movably attach the bar to the walls of the tray or drawer, said bar being slotted on one of its vertical sides to receive and hold a series of guide cards in spaced relationship.

35 2. In combination with a filing tray, a spacing bar for guide cards, a collar slideable with frictional engagement on said bar and tray-engaging means carried by said collar.

40 In witness whereof I have affixed my signature.

FRED E. KUNKEL.
